UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA.

MANIFOLDING SALES-BOOK.

1,236,666.

Specification of Letters Patent. Patented Aug. 14, 1917.

Application filed March 15, 1916. Serial No. 34,285.

To all whom it may concern:

Be it known that I, EDWARD K. BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to manifolding devices and with respect to its more specific features to manifolding salesbooks.

One of the objects of the invention is the provision of a simple and practical construction of a manifolding salesbook, where-with duplicate, triplicate, etc., copies may be made.

Another object of the invention is the provision of a manifolding salesbook, wherein the pads may be readily inserted and removed with ease and rapidity, and where-with the successive leaves of the several pads may be disposed in convenient position for writing without substantial rumpling thereof.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming part of this specification and wherein similar reference characters refer to similar parts throughout the several views,—

Figure 1 is a perspective view of one embodiment of the invention, and

Fig. 2 is a detail thereof.

It will be apparent from the following disclosure that certain features of the invention may be embodied in forms of salesbooks different from the form specifically disclosed, but, inasmuch as the practical features of the invention are well presented in connection with a manifolding salesbook adapted to make triplicate copies, the invention is herein disclosed in connection with such an embodiment. The numeral 1 indicates a cover or holder of a manifolding salesbook. This cover may consist of a base or bottom member 2 and a top member 3,

hinged to the base member by a flexible joint as at 3', and adapted to fold into position opposite thereto to inclose the pads. At the other side of the base member 2 is hinged a member 4, one face of which is adapted to carry a pad, and this binder member may be another leaf of the cover. The pad carried by the binder member may be of any practical form comporting with the proper operation of the book, and the form herein shown is known as a paragon pad; that is, it is composed of double leaves, one-half of which have stubs bound together, with the other half folded in between. This pad is secured to the binder member by means of a clamp 5, so that it may be removed, and another similar pad substituted therefor. Lying on the pad and bound in with the stubs thereof is a double face carbon sheet 6, which may be disposed between the original and duplicate leaves of the paragon pad. The base member 2 supports another pad 7, in the present instance a pad of tissue leaves, the leaves of the tissue pad being for interposition between the leaves of the paragon pad 8 and on top of the carbon sheet, so that an inscription made upon the outer leaf of the paragon pad will be copied upon the tissue and the underlying leaf. When the inscription has been made the paragon leaf is torn from the pad along a weakened line 8 adjacent the stub portion, the free paragon leaf is torn apart along a weakened line 9, provided therefor, and the binder is elevated or turned around its hinge 10 so as to permit the inscribed tissue leaf to drop beneath the same, whereupon the binder may be permitted to fall upon the inscribed tissue leaf. In order to efficiently secure the tissue pad in operative position and to permit its various movements, and also to provide for efficiently supporting the leaves of the tissue pad as well as to permit this pad to be made of a relatively thin character, the base member 2 of the cover is provided with a holding device of a very simple character, but having many advantageous features when employed in connection with a manifolding salesbook of the character described. This device is secured near one edge of the paragon pad, in the present embodiment at the side of this pad adjacent the free edge of the binder 4. The tissue pad holding device referred to provides a channel 11 extending parallel to the hinge of the binder, and in the present

embodiment it consists of a metallic strip 12 of flexible resilient material having flanges or walls 13 and 14 in planes at angles to the plane of said metallic strip, these flanges being disposed in planes generally normal to the plane of the base member, and converging upwardly. This channel is open at each end for the entry of the tissue pad in a direction lengthwise of the channel, and it 10 will be perceived that said pad may be withdrawn at either end. The walls 13 and 14 of the holding device terminate in a plane above that of the base 2, so that the tissue pad held in the channel may lie nicely upon 15 the paragon pad without undue bending of the tissue pad. One of the walls, as 13, of the holding device is bent away from the other wall, as at 15, and one of the walls is also longer than the other, in order to facilitate 20 the entry of the pad between the walls. It will be observed that the normally disposed walls of the channel are continuous longitudinally of the channel, so that a pad in position between the walls will be supported on the edges of the inner wall 13 at 25 all points throughout the length of the pad.

The best manner of applying the tissue pad to its holder is to grasp this pad when closed and direct the edge adjacent the binding staples or sewing between the walls of the holder at one end of the holder, the edge of the pad being pressed against the longer wall and readily slid between the walls, the bent back portion of the other 25 wall facilitating the entry. The bound edge of the tissue pad having been started between the walls, the pad may be slid completely into its operative position. Should the tissue pad be a short one, as is sometimes desired when only a portion of a record is to be made on the tissue pad, the holder hereinbefore described efficiently retains the shorter pad and permits it to be adjusted longitudinally of the holder, as 45 desired. Furthermore, it will be noted that the normally disposed walls of the holder will be presented opposite the leaves of the tissue pad at all points of the latter, so that the pad will be efficiently and positively supported by the holder walls 50 throughout the length of the pad, and this is the case whether the tissue pad be as long or shorter than the holder. Unlike some other forms of pad holding devices, practically no instruction for applying and removing the pad from the holder is required. The manner of inserting the tissue pad in 55 operative position is apparent to the operator practically upon inspection of the device.

Thus by the above described construction are accomplished, among others, all of the objects of the invention hereinbefore referred to.

As many changes could be made in the 85 above construction and many apparently widely different embodiments of this invention could be made without departing from the scope thereof, it is intended that all matter contained in the above description or 70 shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween. 80

Having described my invention, what I claim as new and desire to secure by Letters Patent is:

1. A manifolding salesbook comprising, in combination, a cover comprising leaves hinged together, one of said leaves being adapted to support a pad, and another of said leaves having a channeled member extending parallel to said hinge, adapted to secure another pad in operative relation to 95 said first mentioned pad, the walls of said channel being approximately normal to the plane of the cover leaf and terminating in a plane above that of the cover leaf.

2. A manifolding salesbook comprising, in combination, a cover comprising leaves hinged together, one of said leaves being adapted to support a pad, and another of said leaves having a channeled member extending parallel to said hinge adapted to 100 secure another pad in operative relation to said first mentioned pad, the walls of said channel being approximately normal to the plane of the cover leaf and terminating in a plane above that of the cover leaf, one of said walls being shorter than the other longitudinally of the channel.

3. A manifolding salesbook comprising, in combination, a cover comprising leaves hinged together, one of said leaves being adapted to support a pad, and another of said leaves having a channeled member extending parallel to said hinge adapted to 110 secure another pad in operative relation to said first mentioned pad, the walls of said channel being approximately normal to the plane of the cover leaf and terminating in a plane above that of the cover leaf, the end of one of said walls being bent away from the other wall.

4. A manifolding salesbook comprising, in combination, a cover comprising leaves hinged together, one of said leaves being adapted to support a pad, and another of said leaves having a channeled member extending parallel to said hinge adapted to 125 secure another pad in operative relation to said first mentioned pad, the walls of said

channel being approximately normal to the plane of the cover leaf and converging toward the channel opening.

5. A manifolding salesbook comprising, in combination, a cover member, a pad hinged thereto, and a pad holder supported by said cover member, said holder comprising a metallic strip having flanges forming a pad-receiving channel open at one end, 10 said flanges extending generally parallel to said hinge.

6. A manifolding salesbook comprising, in combination, a cover member, a pad hinged thereto, and a pad holder supported 15 by said cover member, said holder comprising a metallic strip of resilient material, having flanges integral therewith, forming a pad receiving channel open at one end, 20 said flanges extending generally parallel to said hinge.

7. A manifolding salesbook comprising, in combination, a pad-supporting member, a pad connected to said member, a second member carried by said support having a channel, the walls of which are in upstanding position relative to the pad-supporting member, and a second pad having its edge held in said channel and adjustable therein. 25

8. A manifolding salesbook comprising, in combination, a cover member, a pad carried thereby, a channeled member upstanding from said cover member, and a second pad having its bound edge in said channeled member and adjustable in said channel. 30

In testimony whereof I affix my signature, 35
in the presence of two witnesses.

EDWARD KIRBY BOTTLE.
